(57) **CLAIM**

The ornamental design for a radiator extension, as shown and described.

DESCRIPTION

FIG. 1 is a perspective view of a radiator extension of the present invention;

FIG. 2 is a perspective view thereof, in mirror image;

FIG. 3 is a front view thereof;

FIG. 4 is a rear view thereof;

FIG. 5 is a top view thereof;

FIG. 6 is a bottom view thereof;

FIG. 7 is a front elevation view thereof;

FIG. 8 is a rear elevation view thereof; and,

FIG. 9 is a perspective view thereof in a potential environment.

The broken lines illustrate the design's environment and form no part of the claimed design.

This application acknowledges and claims a mirror image of the present design, not shown in the figure drawings, as mirroring elements from one side of a vehicle to the other is well known in the art.
